UNITED STATES PATENT OFFICE.

ENRIQUE MOLINA, OF LIMA, PERU.

APPARATUS FOR TREATING RUBBER.

No. 914,156.

Specification of Letters Patent. Patented March 2, 1909.

Application filed August 5, 1908. Serial No. 447,063.

To all whom it may concern:

Be it known that I, ENRIQUE MOLINA, a citizen of the Republic of Peru, and a resident of Lima, Peru, have invented a new and Improved Apparatus for Treating Rubber, of which the following is a full, clear, and exact description.

This invention relates to certain improvements in apparatus for use in treating the juice of the rubber tree, to coagulate or solidify the same and thus form crude rubber.

The object of the invention is to so support the liquid that it may be continuously agitated while being subjected to the action of smoke and gaseous products of combustion, from which all soot, ashes and other solid particles have been removed.

Reference is to be had to the accompanying drawings forming a part of this specification, in which similar characters of reference indicate corresponding parts in all the figures.

Figure 1 is a central vertical section through an apparatus constructed in accordance with my invention, said section being taken on the line 1—1 of Fig. 2; Fig. 2 is a top plan view of the apparatus; Fig. 3 is a perspective view of the receiver or drum which holds the material to be treated; and Fig. 4 is a perspective view of a sheet of crude rubber as it appears after removal from the receiver.

My apparatus includes primarily means for supporting and continuously agitating the material, together with means for delivering into contact therewith gaseous products of combustion.

In the specific form illustrated in the drawings, my receiver is in the form of a hollow drum 10 having open ends, and inwardly-directed flanges 11 adjacent to said ends, whereby when the drum is supported in a horizontal position, a limited quantity of liquid may be contained therein. The drum is secured to an axle 12 by means of one or two spokes 13 or bars 13 at each end thereof, and the axle is preferably so mounted that the drum may be moved longitudinally without inclining it. For generating the smoke and delivering the same into contact with the drum, I provide a casing in the form of two sections, one forming a lower fire chamber 14 and the other forming an upper smoke chamber 15. The lower chamber is preferably of truncated conical form and serves as a base for supporting the remainder of the apparatus. Within the lower section 14 is a grate 16 upon which a

fire may be built. In the side of the section above the grate, I provide a suitable substantially air-tight door 17 to permit the fuel to be inserted, and below the grate is a second door 18 through which ashes may be removed. The upper section or chamber 15 is preferably of substantially rectangular form and is provided with an opening in the lower portion thereof through which the smoke and gases from the lower chamber may enter.

At the upper end of the lower section, I provide means for separating out any solid particles which may be carried along in the smoke, such, for instance, as soot or ashes. This means preferably comprises a screen or diaphragm 19 of reticulated metal, for instance, wire gauze, and mounted upon this diaphragm is a mass of pebbles, broken stone or other suitable material 20. The smoke from the fire may pass upward through this mass of pebbles to the smoke chamber and into both ends of the drum or receiver, so as to contact directly with the material being treated. From the upper portion of the lower chamber I provide a suitable outlet pipe 21 for the smoke, and from the upper chamber I provide a similar pipe 22 delivering to the first-mentioned pipe. The two pipes are provided with corresponding dampers 23 and 24, so that the smoke may be delivered through pipe 21 without passing through the smoke chamber, or it may be prevented from passing through the pipe 21 and caused to flow into contact with the receiver. The smoke chamber is provided with an entrance opening, so disposed that the drum may be removed from the smoke chamber without tilting or inclining the same. As shown, the smoke chamber is provided with a circular opening of substantially the same size as the drum and in axial alignment therewith. The opening is preferably threaded and normally closed by a threaded disk or closure 25 having a central opening therethrough, constituting a bearing for the axle or spindle 12 of the drum. The axle is hollow for a portion of the length thereof and the end of the smoke chamber opposite the closure 25 is provided with an inwardly-extending pin or pivot 26 disposed within the hollow end of the axle. The drum is somewhat shorter than the smoke chamber so that the smoke may freely enter the open end of the drum, and the pin or pivot 26 is of such a length that during the removal of the drum from the smoke cham-

ber the hollow axle does not pass out of contact with the pin 26 until after the end of the drum has passed into the end opening of the smoke chamber.

5 In the use of my improved apparatus, the closure 25 is removed and the drum supported with one end thereof extending out through the opening in the smoke chamber and the inner end supported upon the end of 10 the pin or pivot 26. The drum is thus supported at both ends so that it remains in a horizontal position, and the open end is freely exposed so that the desired quantity of material to be treated may be poured into 15 the open end and retained within the drum by the end flanges 11. The drum is then moved inward axially so that it is supported entirely upon the pivot 26, and the closure 25 is then inserted to constitute a bearing for 20 the axle and help support one end of the drum. A fire is built on the grate bars 16 and by closing the damper 23 the smoke is compelled to pass upward through the purifier and into the smoke chamber. The drum 25 is continuously rotated and the liquid caused 25 to flow over the inner surface of the drum so as to be exposed to the action of the smoke and gaseous products of combustion in a very thin film. After the material has been treated 30 to the desired extent, the damper 23 may be opened and the smoke permitted to pass up the pipe 21.

My improved apparatus is especially adapted for use in the treatment of the juice 35 or sap of the rubber tree, to coagulate or solidify the same as a first step in the formation of rubber. The smoke purifier prevents any solid particles from passing into the cylinder but does not affect the gases other 40 than to slightly cool them. The purifier thus serves the additional purpose of preventing the smoke chamber from becoming heated to a high temperature. The liquid under the action of the smoke slightly solidifies 45 or coagulates and at the end of the process forms a solid lining within the drum.

To remove the material from the drum, I preferably cut a slit along one side thereof from end to end, and by folding in the material at one side of the cut or slit it may be 50 readily withdrawn in a sheet from the open end of the drum. The material after being removed will appear substantially as shown in Fig. 4, and will be in the form of a hollow 55 cylinder A having a wall of substantially uniform thickness and having a slit B along one side.

Although the apparatus above described is especially designed for use in the treatment of rubber yet it is evident that it may be employed for various other purposes in which it is desired to treat a substance with gaseous products of combustion while being continuously agitated.

Having thus described my invention, I 65 claim as new and desire to secure by Letters Patent:

1. In an apparatus of the character described, a casing having two communicating chambers, means for supporting the burning material within one of said chambers, means for supporting and agitating the material to be treated in the smoke chamber, and a mass of pebbles within the communication between said chambers. 75

2. In an apparatus of the character described, a casing having an opening in one end thereof, a pivot extending inwardly from the opposite side of said chamber, and a rotatable drum within said chamber and having a hollow axle mounted upon said pin and said drum being removable through said opening. 80

3. In an apparatus of the character described, a chamber having a circular opening 85 in one end thereof, a closure therefor, a pin extending into said chamber from the side thereof opposite said closure, a hollow rotatable drum within said casing, and an axle therefor having one end extending through 90 said hollow closure and having the opposite end thereof hollow and receiving said pin.

4. In combination, a casing having a truncated conical base forming a fire chamber, a rectangular upper portion forming a smoke 95 chamber, means for purifying and cooling the smoke passing from said fire chamber to said smoke chamber, and means for supporting the material to be treated within said smoke chamber. 100

5. An apparatus for treating rubber, including a smoke chamber, a rotatable drum within said chamber and having at each end thereof an inwardly-directed flange, a fire chamber, and means for purifying and cooling the smoke passing from said fire chamber to said smoke chamber. 105

In testimony whereof I have signed my name to this specification in the presence of two subscribing witnesses.

ENRIQUE MOLINA.
